Inventor:

John B. Baxter,
by J. B. Baxter Atty's:

UNITED STATES PATENT OFFICE.

JOHN B. BAXTER, OF TROY, NEW YORK, ASSIGNOR TO COVERT MANUFACTURING CO.,
OF TROY, NEW YORK, A CORPORATION OF NEW YORK.

DESIGN FOR A ROPE-THIMBLE.

52,110.

Specification for Design   Patented June 18, 1918.

Application filed December 17, 1917. Serial No. 207,634. Term of patent 14 years.

To all whom it may concern:

Be it known that I, JOHN B. BAXTER, a citizen of the United States of America, and resident of Troy, in the county of Rensselaer and State of New York, have invented a new and original Design for a Rope-Thimble, of which the following is a specification, reference being had to the accompanying drawing forming part hereof.

In the drawing, Figure 1 is a perspective view of the rope thimble, illustrating my new design,

Fig. 2 is a side view of the same, and
Fig. 3 is a top view.

I claim:

The ornamental design for a rope thimble,
as shown.

JOHN B. BAXTER.
